UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

YARN SPOOL.

Application filed September 1, 1923. Serial No. 680,529.

To all whom it may concern:

Be it known that I, EDGAR F. HATHAWAY, a citizen of the United States, and resident of Wellesley, in the county of Norfolk and 5 State of Massachusetts, have invented certain new and useful Improvements in Yarn Spools, of which the following is a specification.

This invention relates to yarn spools of 10 the type such as are used in tube frames for pile fabric weaving, although novel features of this construction may be used in yarn-spools for other apparatus as well.

According to previous commercial practice, 15 yarn spools have commonly been made of solid wooden cylinders to whose opposite ends were glued, or otherwise secured, disks of larger diameter to form flanged heads, journal pins being inserted at the opposite 20 ends axially of the spool to support the same.

The present invention is intended to provide a yarn-spool that is very strong and durable and at the same time is light in weight 25 which is a material advantage especially for yarn-spools used in tube frames. To cause satisfactory adherence of the yarn ends to the barrel of the spool, when the yarn thereon is nearly exhausted, I provide 30 the metal or tubular barrel with a special surface adapted to promote adhesion of the 35 yarn to the barrel so as to prevent slip.

These and other features of the invention 40 will be explained in the following specification and will be defined in the claims hereto annexed.

In the drawings I have illustrated various 45 forms of construction and arrangement embodying the principles of this invention, in which:

Figure 1 is a side elevation of a complete 50 spool embodying the features of my invention, a portion of the barrel and one head being shown in central cross section.

Figure 2 is a transverse sectional view 55 of the spool shown in Figure 1.

Figures 3 and 4 are longitudinal central 60 sections showing modified forms of the spool head.

Figure 5 is a cross section showing a modified 65 form of spool barrel.

In the practice of the invention, according 70 to the form illustrated in Figures 1 and 2, I provide a tubular metallic barrel 1, which 75 is provided with a yarn-retaining anti-slip

surface which, in this case, comprises a sheet of emery cloth, sand paper or the like, as shown at 2, which is wound snugly around the barrel between the heads and may be glued or otherwise secured thereto to maintain it in firm and smooth engagement with the barrel.

The heads or flanges of the spool comprise an outer or flange ring 3, having an outer flange 4 and an inner flange 5, extending 65 substantially parallel to the axis of the spool, the inner flange forming a snug fit over the outer end of the barrel.

The inner member of the head comprises a ring 6, having an axially extending flange 70 7 which fits snugly inside of the end of the spool barrel.

When the spool head members are assembled in operative position, as shown in Figure 1, they may be spot-welded or otherwise rigidly secured to the interposed end portion of the tubular barrel.

The central opening through the inner head is of a size adapted to receive a tubular socket 8, which is provided with a shoulder 9, abutting against the outside face of the head 6. The outer edge portion of the socket 8, is crimped inwardly to form an annular shoulder, as shown at 10, which shoulder forms a stop limiting the upward movement of the journal pin 11, which, in this instance, has a larger diameter fitting inside the bore of the socket 8 and is normally pressed outward yielding by a helical spring 12 inserted in the socket before the 90 pin is inserted and the edge is crimped down to keep the pin in place.

To provide still further stiffening for the structure the inner head 6, is provided with an inwardly projecting flange 6^a, extending 95 a short distance along the exterior of the socket to afford elongated support thereof.

The form of head shown in Figure 3 shows a somewhat different form of bracing the socket member 8, and in this case the inner 100 head 16 is provided with an outer flange 16^a for attaching it inside the barrel. In the central opening of the head 16 is secured, by spot-welding or otherwise, a flanged tube 17 whose flange lies against the inside face of 105 the head 16 and whose tubular portion projects outwardly beyond said head to surround and support the socket member 8 containing the journal pin 10.

In the form shown in Figure 4, the inner 110

head 16 has the same construction as the form shown in Figure 3, and has attaching channel rings 20 and 21, rigidly secured to the inner and outer faces of the head 16, respectively, with their axial or tubular members forming a snug contact with the exterior face of the socket member 8 which carries the journal pin 10. This form, it will be seen, provides a very rigid reenforcement 10 for the socket piece and for the inner head.

In Figure 5 is shown a modified form of barrel which comprises a tubular member 22 rolled up from a sheet of metal with the adjacent longitudinal edges turned inwardly 15 in the form of inwardly projecting flanges 23, so as to provide a shallow longitudinal recess or trough for the reception of a clamp which holds the inner ends of the wound-on tuft yarn, according to well known practice.

In this case the yarn-engaging surface comprises a piece of pile fabric, such as velvet, carpet or the like, whose pile projects outwardly usually in an oblique or inclined direction to the plane of the fabric forming, thereby, a series of very numerous closely arranged spines which, by their engagement with the yarn ends, provide an excellent anti-slipping surface.

30 What I claim is:

1. A yarn spool for weaving embracing a tubular barrel, a head comprising inner and outer laterally flanged disks engaging said barrel in lapped relation and firmly secured thereto, and a journal mounted centrally in said inner disk to rotatably support said spool substantially as described.
2. In a yarn spool the combination of a tubular barrel, a peripherally flanged circular disk secured to said barrel with its peripheral flange in lapped relation to the bar-

rel and a spool supporting journal mounted centrally of said disk to rotatably support said spool, substantially as described.

3. In a yarn spool, the combination of a tubular barrel, a flanged disk rigidly secured to the end portion of said barrel with its flange in lapped relation to the barrel, a socket member centrally secured to said disk and a journal mounted in said socket to form 50 an axis for the rotation of the spool substantially as described.

4. In a yarn spool, the combination of a tubular barrel, a spool supporting head comprising a transversely arranged disk having 55 flanged connections with the end of said barrel and a central socket member having flanged connection with said disk and a journal mounted in said socket, substantially as described.

5. In a yarn spool, the combination of a longitudinal barrel for receiving the yarn, a journal retaining head embracing a circular disk flanged peripherally to form a lateral attaching member adapted to be secured in lapped relation to the end portion of said barrel, and an axial journal centrally mounted in said head and having flanged connection therewith for maintaining it in operative position.

6. A yarn spool embracing a tubular barrel and circular heads secured thereto by flanged connections, supporting journals mounted centrally of said heads, and a pile fabric covering for said barrel arranged to 75 hold the yarn against slipping circumferentially of the spool, substantially as described.

In witness whereof, I have subscribed the above specification.

EDGAR F. HATHAWAY.
